UNITED STATES PATENT OFFICE.

ALFRED G. LEGGE, OF BROCKTON, MASSACHUSETTS.

SHOE-FORM.

1,109,771.

Specification of Letters Patent.

Patented Sept. 8, 1914.

Application filed January 8, 1913. Serial No. 740,785.

To all whom it may concern:

Be it known that I, ALFRED G. LEGGE, a citizen of the United States, residing at Brockton, county of Plymouth, State of Massachusetts, have invented a certain new and useful Improvement in Shoe-Forms, of which the following is a specification, reference being had therein to the accompanying drawings.

- 10 My invention has for its object to provide an improved shoe form which shall be capable of use in shoes of substantially all styles of toes in shoes of a given width. Heretofore, hollow shoe forms of leather-board or similar material have in general been capable of use only in shoes of a single width and style of toe, that is for the particular form of toe, whether low or high, wide or narrow, for which the shoe form 20 was originally designed to be used, and duplicating in shape the last on which the shoe was made. As it has generally been necessary to make a different shoe form for each width, and for each style of toe, the 25 shoe manufacturer has been obliged to procure different forms for each style of shoe of a given width, and the maker of shoe forms has been obliged to provide a last of suitable shape for each of these shoe forms. 30 This has resulted in great expense to the maker of shoes, who is obliged to procure a large assortment of expensive shoe forms, and even with the greatest care is likely to find that he is short of some size or style. 35 It has also resulted in large expense to the manufacturer of shoe forms, not only on account of the variety of lasts required, but because shoe forms cannot be made up in advance and kept in stock. While it has been 40 customary to provide shoe forms with adjustments both as to width and length these adjustments have been primarily for the purpose of allowing the inevitable variations between shoes of the same width and 45 style and to enable the shoe form to be expanded into the shoe; and while these adjustments may possibly, in some instances, have been used to adjust the form for use in a width next to that for which it was intended, nevertheless, so far as is known to me, no attempt has ever been made to provide a shoe form capable of use in the entire range of shoes of a given width but having different styles of toes. 50 The shoe form embodying my invention is capable of use in all ordinary different styles

of shoes of a given width, regardless of the style of toe, that is regardless of whether the shoes have wide toes, narrow toes, high toes or low toes. It therefore results that it 60 is necessary for the shoe manufacturer to buy only a single shoe-form for each width of shoe, and this will fit all the styles of toes made in that width. Also the maker of the shoe form has only to provide himself with 65 but a single width of last on which to make a shoe form to fit all styles of shoes of that width. Great economy results.

The shoe form embodying my invention is capable of use with all styles of shoes of a 70 given width, except that it is not capable of use in shoes having no boxes or toe stiffeners, and when used with any of the various sizes for which it is intended it gives to the shoes exactly the smoothness and elegant appearance 75 presented when a form made especially for that width and style of shoe is employed.

The invention will be fully understood from the accompanying drawings, taken in 80 connection with this specification and the novel features are pointed out and distinctly defined in the claim at the close of the specification.

In the drawings, Figure 1 is a view in 85 perspective of a shoe form embodying my invention. Fig. 2 is a perspective bottom view of the shoe form shown in Fig. 1.

Referring now to the drawings, there is shown at A the fore part and at B the heel 90 part of the shoe form, these members being preferably made of leatherboard or other suitable resilient and somewhat flexible material and overlapping each other at the middle of the shoe form. The fore part A 95 has the inturned edges a a which lie in contact with the insole of the shoe when the shoe form is in place. These inturned edges support the shoe form in proper position vertically so that when the shoe form is expanded a uniform pressure will be exerted on the upper. The fore part or toe part A terminates at a point just forward of the rear edge of the box, as it is unnecessary to support this part of the shoe by the shoe 100 form. The two inturned edges a a of the toe part are connected by means of some adjusting mechanism by means of which the toe part may be widened or expanded when it is in place in the shoe. In practice 105 I use a toggle joint composed of two members a and f pivoted at g and h respectively

to the said inturned edges, and at *i* to each other, one of said members being provided with a thumb piece *j*. The toggle joint is preferably made with a long throw so that it will be capable of moving the sides of the shoe form for the distance required by the difference in width between the narrowest and widest toes of shoes of the width with which form is to be used.

10 The two parts of the shoe form are pivotally connected and means are provided for adjusting the parts of the shoe form longitudinally. In the drawings, I have shown a pivot *C* on the fore part and slideable in a slotted plate *D* on the heel part. Movable on the pivot *C* is a notched latch *E* provided with a series of notches *k* one of which engages a projection *l* on the plate *D*. Both sides of the shoe form are provided with similar means of adjustment. The mechanism just described for adjusting the length of the shoe form, forms the subject matter of my Letters Patent of the United States granted Oct. 7, 1918, No. 1,074,723, and therefore is not claimed herein, but any other suitable means for adjusting the length of the shoe form may be employed.

15 In making my improved shoe form I use as a starting point for the measurements of length, a point at the waist of the form which is about the point *M* in the drawings, instead of measuring from the tip of the toe as I have heretofore done in the manufacture of ordinary shoe forms. I also make the shoe form relatively longer from this point to the heel so that the form will be certain to be pressed firmly into the instep of the shoe.

20 When the form is put in place in the shoe, the length is adjusted so that the heel end will rest firmly against the counter of the shoe while the toe part is forced against the vamp of the shoe and extends under the box so that the front end of the shoe form does not bring up against the toe of the shoe. The toe part of the shoe form is then expanded laterally to stretch the adjacent portions of the shoe until they lie smoothly over

the form, this being accomplished by the 50 toggle joint. If the shoe has a broad or high toe, the front end of the toe part of the form is free to expand, but if the toe is narrow or low the front end of the toe part of the form is correspondingly contracted 55 or curled together where the toe part is pushed forward under the box. This capacity for adjustment and adaptation to different toes of shoes results from the fact that the end of the shoe form being terminated on a line at right angles to the length of the sole and at a point just forward of the rear edge of the box offers no resistance to contraction except that of the natural resiliency of the material. As this portion extends under the box toe, the shoe presents the same appearance as if the form reached to the toe of the shoe.

25 The capability of my improved resilient and somewhat flexible form to accommodate itself to shoes of different styles, or shoes having toes of different heights and widths, is due to the fact that the form has a truncated toe portion and does not extend to the end of the inside of the shoe, so that when 75 said improved form is inserted in a shoe having a narrow or low toe it is free to contract or curl together, at its toe portion, as above stated, which it could not freely do if it had a complete toe portion which would afford a bracing connection between the sides of the toe portion of the form and thus prevent a form having a wide or high toe portion from contracting so as to fit a narrow- or low-toed shoe.

30 What I claim is;

A shoe form composed of resilient and somewhat flexible material and having a truncated open-ended toe portion which will adapt itself, under pressure, to shoes having 80 different shapes or styles of toes.

In testimony whereof I affix my signature, in presence of two witnesses.

ALFRED G. LEGGE.
